SNOWPLOW

Archie O. Williamson, Minneapolis, Minn., assignor to Wm. Bros. Boiler & Manufacturing Co., Minneapolis, Minn., a corporation of Minnesota

Application August 31, 1946, Serial No. 694,217

6 Claims. (Cl. 37—43)

1

This invention relates to snow plows and more particularly to rotary snow plows of the type used for removing snow from large horizontal areas such as airport landing strips and the like. In airports the landing strips must be maintained free of snow and ice throughout the winter season in order to permit continuous and safe operation of air traffic. The strips are wide and long, and although the snowfall may only be a few inches in depth, the total volume of snow that must be removed is tremendous. Furthermore, the snow removal must be accomplished at high speed since the removal must be carried on while air traffic continues.

Ordinary highway snow removal equipment has been found to be deficient in speed of operation and in plowing width capacity.

It is an object of the present invention to provide an improved snow removal apparatus capable of removing and dispersing snow over great widths and at exceedingly high speeds, despite obstacles usually encountered at airports and similar installations.

It is a further object of the invention to provide an improved snow removal apparatus of the rotary or snow slinging type capable of gathering snow at high speeds into the casting section of the apparatus.

It is a further object to provide an improved snow gathering mechanism capable of being elevated and depressed instantly to and from any desired height and yet capable of being folded into an out-of-the-way position.

Other and further objects of the invention are those inherent in the apparatus herein illustrated, described and claimed.

The invention is illustrated in the drawings in which:

Figure 1 is a front elevational view of a rotary snow plow incorporating the invention in issue;

Figure 2 is a fragmentary side elevational view of the snow plow;

Figure 3 is a fragmentary plan view of the apparatus of the invention; and

Figure 4 is an enlarged fragmentary plan view illustrating the several operating positions of the invention.

Throughout the drawings corresponding numerals refer to the same parts.

Referring to the drawings there is illustrated a conventional rotary snow plow which is shown over the bracket 10 in Figure 1. The snow plow moldboard is symmetrical about the center line 11. The right half of the plow consists of a moldboard section generally designated 11 having

2

ing converging portions 12 and 13 which convey the snow to a rotary snow-casting wheel 14. The second half of the plow 11' is composed of moldboard 15 and 16. These moldboards likewise convey snow to a second rotary snow-casting wheel 17. The snow plow illustrated is of the general type shown in Patent No. 2,337,108. The snow-casting wheels 14 and 17 cast the snow vertically into a pair of chutes 20 and 21, which in turn discharge into a snow conveying shroud 22 that terminates in the snow-directing lip plate 23. The plate 23 is curved and has partial front and rear side plates and is pivoted at 24. A hydraulic mechanism 25 is attached to the frame of the snow plow and to the snow elevating lip 23 so that the latter may be moved arcuately in the direction of the double arrow 26 for directing the snow far or near or for loading operations.

At each side of the main snow plow assembly 20 there are provided a pair of bank-cutting knives 27 and 28 which are held vertically and serve to cut down the edges of snow banks where the plow is used in heavy drifts. At the front of the snow plow there is also provided a snow-chopping mechanism generally designated 30 which is also shown in Patent No. 2,337,108. The snow-chopping mechanism is chain driven and serves preliminarily to break up snow from drifts and feed it directly to the moldboard portions 12, 13, 15 and 16 and thence to the casting wheels 14 and 17.

As illustrated in Figure 2 the entire snow plow arrangement is mounted on the front end of a heavy automobile vehicle generally designated 40 having front wheels 41 and two or more rear wheels not illustrated. On the rear platform of the automotive vehicle there is provided an ample power unit 42 which drives the propulsion shaft 43 of the snow plow through a plurality of V-belts illustrated at 44. The drive shaft 43 operates through universal 43' and drive shaft extensions 45, and thence extends through gearing in housing 47 (Figure 3) to the rotary wheels 14 and 17 of the snow plow.

The details of the particular basic snow plow unit above described form no part of the present invention and are included merely by way of illustrating the basic machine on which the extraordinary snow gathering wings of the present invention are utilized. It is therefore to be understood that other types of rotary snow plows may be utilized where desired.

Referring to Figures 1, 2 and 3, at each side of the basic rotary snow plow 10 there is provided an extraordinary snow gathering wing, the right wing being illustrated at 50 and the left wing at

51. These wings are mounted so as to extend outwardly and forwardly of the snow plow unit, as illustrated in Figure 3, and are utilized when the plow is used for gathering in a wide swath of snow of relatively small depth. The condition for which the extraordinary snow gathering wings are most useful is an airport clearing work where it is desired to clean the runway strips of snow at a high rate of speed with maximum clearing width. In many conditions the snowfall may be only a few inches or slightly more in depth. The total amount of snow which is gathered and removed is very large even though the depth is not very great. The snow gathering wings 50 and 51 are mounted upon a pair of vertical pivot slides 52 for wing 50 and 53 for wing 51. The snow gathering wings 50 and 51 are similar right and left units and therefore only one need be described.

As shown in Figure 2 the slide 52 is attached to the moldboard of the main plow unit by upper and lower brackets 54. The slide 52 is preferably a rod or tube of circular cross section and it therefore not only serves as a slide but also as a pivotal mounting for the tubular sleeve 55. The sleeve 55 is attached by means of brackets 56 and 57 to the snow gathering wing 50 and hence the snow gathering wing 50 is capable of being rotated on the rod 52 in the manner of a hinge joint. The inner edge 58 of the snow gathering wing is shaped to fit the adjacent front side edge of the main snow plow moldboard so that when the wing 50 is in position shown in Figure 3, the snow flows along wing 50 in the direction of arrow 59 and thence onto the moldboard of the plow 10 and against the rotary snow-casting wheels 14 and 17.

The position of the wing 50, as shown in Figure 3, is maintained by a toggle brace composed of links 60 and 61 which are hinged together at 62. The link 60 is pivotally attached to the snow gathering wing by means of the pivot bolt 64, and link 61 terminates in a tubular sleeve 65 which, like sleeve 55, is arranged to slide vertically upon a vertical slide rod, namely rod 66. The rod 66 is likewise supported from the main snow plow 10 by means of a pair of brackets 67 and 68 which are attached to the snow plow housing and suitably braced. From the toggle pivot 62 there extends a link 69 which is attached to the wing moldboard 50 by a suitable removable bolt 70, as illustrated in Figure 2. When the link 69 is in place the toggle 60—61 is hence prevented from moving from the angular arrangement shown in Figure 3, and hence a bracing force is transmitted from the vertical slide 66 through the sleeve 65, toggle link 61, bolt 62, toggle 60, bolt 64 to the snow gathering wing 50, which is accordingly held in place in the position shown in Figure 3. When it is desired to fold the snow gathering wing alongside the main snow plow 10, the link 69 is removed or disconnected at one or the other of its ends, and the toggle 60—61 then pivots about its toggle bolts 62 and folds to the dotted line position shown in Figure 4. This accordingly permits the snow gathering wing 50 to pivot on the vertical pivot rod 52, and it likewise assumes a position as shown in the dotted lines of Figure 4. It will also be noted that during this motion the toggle link 61, which terminates at sleeve 65, likewise simply pivots around the rod 60. The entire snow gathering wing and its toggle bracing arrangement accordingly folds backwardly against the side of the snow plow where it is out of the way and per-

mits the snow plow to be used in heavy drifts or moved through narrow places.

In airport snow removal work particularly, the snow gathering wings 50 must be capable of rapid vertical adjustment so as to clear low ground obstacles. In order to accomplish this purpose there is provided a stirrup brace 74, Figure 2, which is of generally inverted V-shape. To the apex 75 of the V there is attached the piston rod 76 of an hydraulic cylinder 77. The bottom of the hydraulic cylinder is mounted on a step 78 which is in turn mounted upon the main snow plow mechanism 10. Accordingly, whenever the hydraulic cylinder 77 is supplied with hydraulic fluid under pressure, the inverted stirrup brace 74 is moved vertically to any desired position under the control of the operator. The hydraulic controls for cylinder 77 and for a similar cylinder for the right hand wing are in the operator cab of the snow plow vehicle.

The stirrup brace 74 is attached at its forward end to a vertical slide 80 which is composed of two sleeves 81 and 82 arranged above and below the sleeve 55. The sleeves 81 and 82 are permanently attached together by the piece 83. Hence, as the stirrup brace 74 is moved vertically, the vertical slide 80 is likewise moved vertically and since the sleeves 81 and 82 are on the upper and lower terminal edges of the sleeve 55, the latter is likewise moved vertically to the position determined by stirrup 74. Hence, by adjusting the position of the hydraulic cylinder 77, the operator may instantly move the entire snow gathering wing 50 to any desired vertical position with reference to ground level.

In order that the wing 50 may be adequately braced at any selected vertical elevation, the stirrup brace 74 is attached at its rear end to a similar bracket generally designated 90 which is likewise composed of a pair of sleeves 91 and 92 solidly attached together by member 93. As the member 90 is moved up and down by the stirrup brace 74, this accordingly moves the sleeve 65 vertically to positions which always correspond to the positions of sleeve 55 on which the snow gathering wing is mounted. Therefore, the toggle attachment is always maintained level, regardless of its height and the angular position of the toggle and the snow-gathering wing 50 therefore does not vary as it is moved up and down.

If desired, the attachment 70 of the link 69 may be by an easily fractured bolt or wooden plug so that the toggle 60—61 will be released in the event the snow gathering wing 50 moves against any solid obstacle.

As many apparently widely different embodiments of this invention may be made without departing from the spirit and scope thereof, it is to be understood that I do not limit myself to the specific embodiments herein except as defined by the appended claims.

What I claim is:

1. In a snow removal apparatus of the casting type having a rotary snow-casting mechanism, the improvement comprising a snow gathering wing extending laterally and forwardly of said snow-casting mechanism, means mounting said wing for direct vertical movement, said means consisting of a forwardly positioned vertical slide means, and a rearwardly positioned vertical slide means, and means for hinged movement about a vertical axis adjacent the edge of said snow-casting mechanism, said last named means including a pair of toggle links pivoted together and con-

nected to the outward end of said wing and the rear slide means respectively, said toggle links being held in an angular position relative to each other by means of a removable link connecting the toggle pivot and the forward slide means.

2. In a snow removal apparatus of the casting type having a rotary snow-casting mechanism, the improvement comprising a vertical pivot slide mounted alongside the snow-casting mechanism adjacent the snow introducing edge thereof, a second vertical slide mounted on the snow-casting mechanism adjacent the first slide but spaced rearwardly in respect to the direction of movement of the mechanism during operation, a snow gathering wing mounted on the first slide for pivotal and vertical sliding movement, a slider mounted on the second slide, a brace from the slider to the snow gathering wing for maintaining it in a forward and sideward extending position and means including a solid link connected to the snow gathering wing and to the slider for simultaneously moving the snow gathering wing and slider vertically.

3. The apparatus of claim 2 further characterized in that the brace comprises a pair of toggle limbs pivoted together and means is provided for maintaining the toggle links in predetermined bracing and folding positions for maintaining the snow gathering wing in snow gathering and folded positions.

4. The apparatus of claim 2 further characterized in that the means for moving the snow gathering wing and slider vertically includes a hydraulic cylinder connected to the link for moving the latter vertically.

5. The apparatus of claim 2 further characterized in that the means for moving the snow gathering wing and slider vertically includes a hydraulic cylinder connected to the snow gathering wing and slider together with a source of hydrau-

lic pressure and operator control means located at a remote operator station on the mechanism.

6. In a snow removal apparatus of the snow gathering and casting type having fixed gathering plow and a rotary mechanism for engaging and casting the gathered snow therefrom, the improvement comprising a pair of vertical slides mounted in the apparatus at one side thereof, one slide being adjacent the edge of the fixed 10 snow gathering plow and the other slider being displaced rearwardly in respect to the direction of motion of the apparatus during use, a first slider mounted on the forward slide and a second slider mounted on the rearward slide, a link fixedly connected to both sliders so that the link and both sliders are movable as a unit, a hydraulic mechanism connected to the link and the snow removal apparatus for moving the link and sliders vertically, a wing pivotally connected at one end to the first slider and a brace connected to the 15 second slider and to the wing for holding the wing in a forwardly and laterally extending position, said wing and brace being thereby vertically movable with the sliders and link as the 20 latter is moved.
